CLAIM

The ornamental design for a greeting card or similar article, substantially as shown and described.

DESCRIPTION

FIG. 1 is a front elevational view of a greeting card or similar article in closed condition showing my new design;

FIG. 2 is a view in elevation thereof, showing the same in open condition;

FIG. 3 is a view in elevation corresponding to that seen in FIG. 2, but showing certain of the component parts in altered relative position;

FIG. 4 is a rear elevational view thereof;

FIG. 5 is a top plan view thereof;

FIG. 6 is a bottom plan view thereof;

FIG. 7 is a side elevational view thereof; and

FIG. 8 is a side elevational view thereof, showing the side opposite that seen in FIG. 7.

FIG. 1

FIG. 4

FIG. 7

FIG. 8

FIG. 5

FIG. 6

FIG. 2

FIG. 3
